UNITED STATES PATENT OFFICE.

REUBEN HAIGHT, OF HUDSON, NEW YORK.

FOLDING BED.

1,339,650.

Specification of Letters Patent. Patented May 11, 1920.

Application filed February 3, 1920. Serial No. 356,001.

To all whom it may concern:

Be it known that I, REUBEN HAIGHT, a citizen of the United States, residing at Hudson, in the county of Columbia and 5 State of New York, have invented certain new and useful Improvements in Folding Beds, of which the following is a specification.

This invention relates to improvements 10 in folding beds.

An important object of the invention is to provide a folding bed which may be quickly and easily placed in the folded position.

15 A further object of the invention is to provide a folding bed which may be readily taken apart for storage or shipment.

Other objects and advantages will be apparent during the course of the following 20 description.

In the accompanying drawings, wherein like numerals are employed to designate like parts throughout the same,

Figure 1 is a plan view of a bed embodying my invention.

Fig. 2 is a side elevation of the same in the extended position.

Fig. 3 is a similar view of the same in the folded position.

30 Fig. 4 is a plan view of one of the side rail supporting members and associated elements.

Fig. 5 is a side elevation of the same showing a portion of one of the side rails 35 in the extended position, parts being shown in section for the purpose of illustration.

Fig. 6 is a similar view showing the side rail in the position it assumes when the bed is folded, and

40 Fig. 7 is a perspective of the hinged portion of one of the side rails.

In the drawings, wherein for the purpose of illustration is shown a preferred embodiment of my invention, the numeral 10 designates the head piece of a bed and 11 the foot piece thereof. The head piece 10 and foot piece 11 are provided with the usual supporting legs 12. Spring supporting rails 13 are provided at each end of the bed having the usual wire spring 14 secured thereto.

Each of the legs 12 is provided with side rail supporting members 15, extending inwardly of the legs 12 for a substantial distance and provided in their free ends with 55 openings 16, having an inner wall 17. A bridge piece 18 extends across the opening

16, spaced from the wall 17 providing a substantially vertical and circular opening 19 for a purpose to be described.

Side rails 20 are mounted on opposite 60 sides of the bed and embody sections 21 and 22. The inner ends of the sections 21 and 22 of the side rails are provided with enlarged heads 23. The heads 23 are preferably provided with flat inner faces adapted 65 to receive the sections of a hinge 24, which may be secured thereto by any suitable means, such as screws or the like. The hinge 24 is provided with a hinge pin 25 extending inwardly beyond the hinge having 70 its inner end terminating in a hook 26 for a purpose to be described. The outer ends of the side rails terminate in down turned ends 27, adapted to be inserted within the openings 19 of the side rail supporting members 15. The ends 27 are preferably arcuate in form and the bridge pieces 18 are preferably circular in cross section, hence these two elements form in effect a hinged joint. Each of the sections 21 and 80 22 is provided adjacent its down turned end with a flange 28 adapted to rest against the upper side of the member 15 and support the side rail sections 21 and 22 when the bed is in the folded position. As shown 85 more clearly in Fig. 5 the down turned ends 27 of the side rails are provided with openings 29 adapted to receive the tongues 30 of bolts 31, slidably mounted upon the upper faces of the members 15 by means of pins 90 32 secured to the member 15 and operating in slots 33.

The operation of my device is as follows:

In order to place the bed in the folded position, as shown in Fig. 3, the inner ends 95 of the rail sections 21 and 22 are raised somewhat and the foot piece 11 moved inwardly toward the head piece 10. When this action takes place the hook 26 of the hinge pin engages the outer edge of and 100 elevates the spring as shown in Fig. 3. The upward movement of the side rail sections also raises the inner ends of the mattress sections so that they assume the positions as shown in Fig. 3. As above explained, the 105 side rail supporting elements 15 extend a substantial distance inwardly of the head and foot pieces, hence when the bed is folded, the said sections occupy a position substantially parallel to and spaced from the head 110 and foot pieces, providing spaces or pockets for the mattress sections, as shown. In

5 folding the bed the down turned ends 27 of the side rails revolve about the bridge piece 18 until the flange 28 contacts the upper face of the supporting element 15. It will be noted that in the folded position of the bed the rail sections 21 and 22 assume vertical position, and there is thus no tendency for these members to drop, unfolding the bed.

10 In order to unfold the bed, it is only necessary to pull the foot piece 11 or head piece 10 outwardly, and elevated parts of the structure will drop and assume their normal position. The bolt 31 is then moved 15 inwardly until the tongue 31 engages within the opening 29, thus locking the parts in position. In order to take the bed apart, it is merely necessary to disengage the bolts 31, whereupon the side rails may be removed 20 by lifting upwardly.

While the form of my invention herein shown and described is to be taken as a preferred embodiment of the same it is to be understood that many changes in the 25 size, shape and arrangement of parts may be resorted to without departing from the spirit of the invention or the scope of the subjoined claims.

What I claim is:

- 30 1. A bed of the type described embodying head and foot pieces, side rail supporting members secured to and extending a substantial distance inwardly of said head and foot pieces, said supporting members being provided with openings, and a pair of hinged side rail sections, the free ends of said sections being provided with down turned ends adapted to be inserted within the openings in said side rail supporting member.
- 35 2. A bed of the type described embodying head and foot pieces, side rail supporting members secured to and extending a substantial distance inwardly of said head and foot pieces, said supporting members being provided with openings and having a substantially circular bridge piece closing the outer end of said opening and a pair of hinged side rail sections, the free ends of said sections being provided with arcuate extensions adapted to be inserted within the openings of said side rail supporting members.
- 40 3. A bed of the type described embodying

55 head and foot pieces, and a spring, side rail supporting members secured to and extending a substantial distance inwardly of said head and foot pieces, said supporting members being provided with openings and having a substantially circular bridge piece closing the outer ends of said openings, a 60 pair of side rail sections, the outer ends of said sections being provided with arcuate extensions adapted to be inserted within the openings of said side rail supporting members, and a hinge including a hinge pin connecting the inner ends of said pair of side rails, said hinge pin extending inwardly and terminating in a hook adapted to engage the spring of the bed when the bed is moved to the folded position.

65 4. A bed of the type described embodying head and foot pieces, side rail supporting members secured to and extending a substantial distance inwardly of said head and foot pieces, said supporting members being provided with openings, a pair of hinged side rail sections, the free ends of said sections being provided with down turned ends adapted to be inserted within the openings in said side rail supporting members, said 70 side rail sections being provided adjacent their free ends with openings, and a bolt slidably mounted upon said supporting members and having a tongue adapted to move into the openings in said side rail 75 sections.

80 5. A bed of the type described embodying head and foot pieces, side rail supporting members secured to said head and foot pieces, said supporting members being provided with openings, and side rail sections mounted upon opposite sides of said head and foot pieces and having down turned ends adapted to be inserted within the openings in said side rail supporting members, 85 said side rail sections being provided adjacent their outer ends with flanges adapted to engage said supporting members when the bed is in the folded position.

90 In testimony whereof I affix my signature 100 in presence of two witnesses.

REUBEN HAIGHT.

Witnesses:

HAROLD E. FRITTS,
FLORENCE KESTENBAUM.
